UNITED STATES PATENT OFFICE.

OTTO W. JOHNSON, OF SAN FRANCISCO, CALIFORNIA.

ROTARY FLUID-PRESSURE DEVICE.

1,297,693.

Specification of Letters Patent. Patented Mar. 18, 1919.

Application filed April 10, 1917. Serial No. 160,922.

To all whom it may concern:

Be it known that I, OTTO W. JOHNSON, a citizen of the United States, residing at San Francisco, in the county of San Francisco 5 and State of California, have invented new and useful Improvements in Rotary Fluid-Pressure Devices, of which the following is a specification.

The present invention relates to improvements in rotary devices which employ movable vanes for transmitting power, such as fluid-operated motors or pumps.

Such rotary devices are rendered inefficient by the fact that the pressure between 10 the shaft and the bearings is very many times as great as that on the vanes, because the effective area of each vane is very much less than that part of the area of the rotor upon which there is a pressure equal to that 15 on the vane. Therefore the friction between the shaft and the bearings, although a small fraction of the pressure between the surfaces of the shaft and the bearings, is a large fraction of the effective pressure. Hence the 20 loss of efficiency is very considerable.

The object of the present invention is to provide means for reducing this loss.

A further object is to provide means for reducing loss by friction between the shaft 30 and ring-carrying vanes.

In the accompanying drawings, Figure 1 is a longitudinal vertical section of a rotary device of the character described constructed in accordance with my invention; Figs. 2 35 and 3 are vertical sectional views on the lines 2-2 and 3-3 respectively; Fig. 4 is a horizontal section thereof; Fig. 5 is a plan view of a rotor detached; Fig. 6 is a broken plan view of a shaft and parts carried thereby.

Referring to the drawing, 1 indicates a 40 horizontal casing, having formed integral therewith a base 2 and conduits 3, either of which can be used for the inlet or outlet conduit, said conduits being adapted to be connected respectively with inlet and outlet 45 pipes, not shown. Connected by bolts 4 to the ends of said casing, but eccentric thereto, are hollow end casings or heads 6, 7, through which extends coaxially a shaft 8, having 50 keyed thereto, as shown at 9, a cylindrical hollow rotor 11 coaxially with said heads and having extensions 12, 13, of which the extension 12 is integral with the rotor, and the extension 13 is secured thereto by bolts 55 14. The rotor 11 is contained in the casing 1, but is eccentric thereto, and the extensions

12, 13, extend into pressure chambers 16 formed in said heads 6, 7, and coaxial therewith, and formed by a cylindrical wall 17 extending inwardly, or toward the rotor 11, 60 from the outer plane wall of said head.

The head 6 is reduced in diameter, as shown at 18, and around the same can rotate a cylindrical flange 19, extending coaxially with the shaft from the extension 13. 65 Said head is still further reduced in diameter, as shown at 21, and around the same can rotate a bushing 22. Around said bushing is a ring 23, from which extends integrally a vane 24 and also two pairs of rings 26, 27, 70 from which pairs extend integrally vanes 28 and 29 respectively. The vane 28 is keyed to the bushing, as shown at 31, but the other vanes are loose thereon. All of these vanes extend through longitudinally extending cylindrical openings 32 in thickened portions 33 of the wall of the rotor, and slide between packing pieces 34 in said cylindrical openings, the outer surfaces of said pieces being cylindrical and the inner surfaces being plane to fit smoothly against the plane surfaces of the vanes. An abutment 36, midway between the conduits 3, contacts 75 with the rotor.

Such being the construction, if pressure 80 fluid be introduced between one of said conduits, it will rotate the rotor by impelling the vanes in succession and will escape by the other conduit and, conversely, if the rotor be rotated by an external force, its vanes will 85 draw in fluid by one of said conduits and propel it through the other.

It will be seen that the pressure fluid will 90 transmit pressure not only to the surface of the vane to propel the rotor, but will transmit the same pressure to the curved surface of the rotor itself, which, being coaxial with the shaft, is ineffective for propelling the rotor, and it will also be seen that the area of this latter surface is very many times as 95 great as that of the former. The friction between the rotor shaft and its bearings depends upon the latter pressure, and while this friction might be negligible if it depended only on the impelling pressure, it is very considerable when it depends upon the pressure exerted upon the rotor, and the loss of efficiency from this cause has been supposed to be about from 15% to 25%.

In my invention I remove this useless 100 pressure of the rotor in the following manner: From each of the divisions, or sections,

of the rotor between pairs of vanes, and midway between said vanes, there extends at each end of the rotor a conduit 37 leading from the fluid pressure chamber 38, inclosed 5 by the vanes, the casing, the rotor and the heads, to a chamber 39 in the adjacent head on the inner side of the extension 12, or 13, as the case may be. The extensions are so formed that the pressure fluid escaping 10 through said conduits 37 from the fluid pressure chamber 38 cannot escape from said pressure chamber 39. The combined lengths of the pressure chambers 39 are equal to the length of the pressure chamber 38, and since 15 the radii of the rotor and extensions is the same, the combined areas of the extensions on which there is outward pressure is equal to the area of the rotor on which there is an equal inward pressure. Consequently, no 20 pressure on the rotor due to the pressure fluid is transmitted to the shaft.

The advantage of providing a bushing between the reduced portion 21 of the head and the rings carrying the vanes is that the 25 rotary movement of the vanes and rings relatively to each other, and, therefore, also of the bushing which is secured to one of the vanes, is but slight, and there is very little wear thereon, and while there is considerable 30 relative movement, and consequent wear, between the vanes and the reduced portion of the head, this is taken up by the bushing, which can easily be replaced from time to time.

35 Since all of the vanes are mounted on the bushing, the centrifugal forces acting on the vanes will practically counter balance each

other, so that the force acting in the bushing due to this cause will be practically eliminated.

I claim:—

1. The combination of a casing having inlet and outlet passages and end casings, a rotor rotating in said central casing and having extensions into said end casings, said 45 extensions forming pressure chambers on their inner sides, vanes forming with said rotor and casing, central pressure chambers, and said rotor having conduits leading from each of the latter pressure chambers to a 50 corresponding one of the former chambers.

2. The combination of a casing having inlet and outlet passages and end casings, a rotor rotating in said central casing and having extensions into said end casings, said 55 extensions forming pressure chambers in their inner sides, vanes forming, with said rotor and casing, central pressure chambers, and said rotor having oblong conduits leading therethrough from each of the latter 60 pressure chambers to a corresponding one of the former chambers.

3. The combination of a shaft, a casing eccentrically surrounding said shaft, a rotor within said casing and concentrically surrounding said shaft, a bearing for the shaft having a cylindrical extension eccentrically surrounding said shaft, a bushing around said extension, and rings around the bushing and having vanes extending through 65 holes in the rotor and contacting at their outer edges with said casing, one of said rings being secured to the bushing.

OTTO W. JOHNSON.
